Primary Examiner—James Gandy

Assistant Examiner—T. Chase Nelson

(74) Attorney, Agent, or Firm—Harness, Dickey & Pierce,
P.L.C.(57) **CLAIM**The ornamental design for an arbor for circular saw blades,
as shown and described.**DESCRIPTION**FIG. 1 is a front perspective view of an arbor for circular saw
blades (the broken line showing of the saw blade is for
environmental purposes and is not considered part of the
design);

FIG. 2 is a front view thereof;

FIG. 3 is a top view thereof;

FIG. 4 is a right side view thereof (the left side view is the
same as the right side); and,

FIG. 5 is a rear view thereof.

The broken line showing portions of the arbor in all of the
views is for illustrative purposes only and forms no part of
the claimed design.**1 Claim, 1 Drawing Sheet**FIG 1
